(57) **CLAIM**

I claim the ornamental design for an electrical junction box, as shown.

DESCRIPTION

FIG. 1 is a perspective view taken from the front and one side of the design;

FIG. 2 is a front elevational view of the design shown in FIG. 1;

FIG. 3 is a right side elevational view of the design shown in FIG. 1;

FIG. 4 is a rear elevational view of the design shown in FIG. 1;

FIG. 5 is a left side elevational view of the design shown in FIG. 1;

FIG. 6 is a top elevational view of the design shown in FIG. 1;

FIG. 7 is a bottom elevational view of the design shown in FIG. 1;

FIG. 8 is a perspective view of the design shown in FIG. 1 with the fasteners in the open position;

FIG. 9 is a perspective view taken from the front and one side of a variation of the design shown in FIG. 1;

FIG. 10 is a front elevational view of the design shown in FIG. 9;

FIG. 11 is a right side elevational view of the design shown in FIG. 9;

FIG. 12 is rear elevational view of the design shown in FIG. 9;

FIG. 13 is a left side elevational view of the design shown in FIG. 9; and,

FIG. 14 is a perspective view of the design shown in FIG. 9 with the fasteners in the open position.

The broken line portions in the drawings are for illustrative purposes and do not form part of the claimed design.
